UNITED STATES PATENT OFFICE

FREDERICK K. VREELAND, OF MONTCLAIR, NEW JERSEY

VARIABLE-CIRCUIT ELEMENT FOR RADIO RECEIVING SETS

Application filed April 15, 1928. Serial No. 102,142.

In another application, Serial No. 680,061, filed December 12, 1923, of which the present application is a continuation in part, there are shown, described and claimed certain improvements in radio receiving sets, in which the operations of tuning and compensating are effected through the manipulation of certain mechanical devices which have been found to be of great practical value and 10 adaptable as well to the operation of variable circuit elements other than the variable capacities of that application. In the present application it is the intention to cover these mechanical devices in combination with such 15 a variable circuit element or frequency selective device, such, for example, as a condenser or a variable inductor. In accordance with the invention, there is placed within the panel or closure of the casing of the receiving set and preferably on an axis parallel with the panel, a disc or dial, the periphery of which, preferably having a scale marked thereon, is exposed to view through an aperture in the panel, which may be glazed, and 20 there is also operatively connected with the variable circuit element and with the first mentioned disc or dial, an operating device or hand wheel which may be in the form of a second disc or dial which may or may not have a scale marked on the periphery thereof and which is preferably on a shaft also 25 parallel with the panel and is exposed or projects through another aperture in the panel, presenting in the preferred embodiment at most a segmental portion only for manipulation from the front of the panel.

The invention will be more fully described hereinafter with reference to the accompanying drawing which, as to the several figures presented, is the same as the corresponding figures of the drawings of the application above mentioned and in which:

Figure 1 is a schematic diagram showing a 40 simple embodiment of the invention described in the application above mentioned, with the mechanical devices herein particularly referred to incorporated therewith.

Figure 2 is a face view of a portion of the 50 panel of a radio receiving set, partially

broken out to show the said mechanical devices.

Figure 3 is a view of the same as seen from a point of view in a plane parallel with the panel which itself is shown in section. 55

It is not necessary, in the present case, to enter into any extended description of the radio circuits and related devices shown in Figure 1, it being sufficient for present purposes to state that in the illustrated embodiment of the invention the variable circuit elements are represented as variable capacities C_1, C_2 , the movable plates of which are mounted on alined shafts R_1 and R_2 , preferably parallel with the panel O or closure of the casing and carrying respectively gears G_1, G_2 . The latter are shown as meshing respectively with pinions P_1, P_2 , on a counter shaft Q_1, Q_2 , which in the embodiment shown is also parallel with the panel O and having an adjusting wheel or disc N , which is exposed for manipulation by the finger through a slot O_1 in the panel O , preferably projecting somewhat through such slot, as shown in Figure 3, so as to facilitate manipulation. In 70 the particular construction shown, both shafts R_1, R_2 are rotated simultaneously so that the elements C_1, C_2 are adjusted by a single motion, but it is obvious that so far as the present invention is concerned, it is 75 exemplified in the operation of a single element, such as the element C_2 . On the shaft R_2 of the element C_2 , is a disc or dial M which has a scale marked on its periphery for co-operation with an index I which, in the arrangement shown, is a line on a transparent window I_1 , which may close the aperture through which the dial is viewed and serve to exclude dust from the interior of the receiving set. The whole structure can be conveniently mounted within the panel or closure through which the operating device N is exposed and the disc or dial M is viewed. In 90 the particular arrangement shown the peripheral edge of the operating device N is exposed for convenient manipulation through the aperture O_1 and the scale carried by the disc or dial M is viewed through the aperture I . It will be obvious that the edgewise arrangement of the disc or dial and of the oper- 95 100

ating device has great practical advantages, not only in convenience of arrangement and in protection against the entrance of dust within the receiving set, but in the elimination from the outside of the panel of the usual dials parallel with the face of the panel.

I claim as my invention:

1. In a radio signaling system and in combination with a plurality of tunable circuits, variable instrumentalities one at least thereof being included in each of said circuits for tuning said circuit, an instrument panel having apertures therethrough, a rotatable shaft mounted adjacent said panel, means for rotating said shaft exposed through one of said apertures of said panel, an indicating dial mounted on said shaft and positioned opposite the other of said apertures in said panel, and connections between said shaft and said tuning elements whereby said tuning elements are simultaneously operated by said rotating means and said indicating dial is positioned opposite its aperture to indicate the adjustment of said tuning elements when said shaft is rotated.

2. In a radio signaling system and in combination with a plurality of tunable circuits, variable condensers one at least thereof being included in each of said circuits for tuning said circuit, an instrument panel having apertures therethrough, a rotatable shaft mounted adjacent said panel, means for rotating said shaft exposed through one of said apertures of said panel, an indicating dial mounted on said shaft and positioned opposite the other of said apertures in said panel, and connections between said shaft and said tuning elements whereby said tuning elements are simultaneously operated by said rotating means and said indicating dial is positioned opposite its aperture to indicate the adjustment of said tuning elements when said shaft is rotated.

3. In a radio signaling system and in combination with a plurality of tunable circuits, variable instrumentalities one at least thereof being included in each of said circuits for tuning said circuit, an instrument panel having apertures therethrough, a rotatable shaft mounted within the panel and parallel therewith in a substantially horizontal plane, means for rotating said shaft exposed through one of said apertures of said panel, an indicating dial mounted on said shaft and positioned opposite the other of said apertures in said panel, and connections between said shaft and said tuning elements whereby said tuning elements are simultaneously operated by said rotating means and said indicating dial is positioned opposite its aperture to indicate the adjustment of said tuning elements when said shaft is rotated.

4. In a radio signaling system and in combination with a plurality of tunable circuits, variable instrumentalities one at least thereof

being included in each of said circuits for tuning said circuit, an instrument panel having apertures therethrough, a rotatable shaft mounted adjacent said panel, a second rotatable shaft also mounted adjacent said panel and having an operating device exposed through one of said apertures, transmitting means between said shafts, an indicating dial mounted on the first mentioned shaft and positioned opposite the other of said apertures in said panel, and connections between said shaft and said tuning elements whereby said tuning elements are simultaneously operated by said rotating means and said indicating dial is positioned opposite its aperture to indicate the adjustment of said tuning elements when said shaft is rotated.

5. In a radio signaling system and in combination with a plurality of tunable circuits, variable instrumentalities one at least thereof being included in each of said circuits for tuning said circuit, an instrument panel having apertures therethrough, a rotatable shaft mounted adjacent said panel, means for rotating said shaft exposed through one of said apertures of said panel, an indicating dial mounted on said shaft and positioned edge-wise opposite the other of said apertures in said panel, and connections between said shaft and said tuning elements whereby said tuning elements are simultaneously operated by said rotating means and said indicating dial is positioned opposite its aperture to indicate the adjustment of said tuning elements when said shaft is rotated.

This specification signed this 12th day of April A. D. 1926.

FREDERICK K. VREELAND.
